UNITED STATES PATENT OFFICE.

GEORGE F. CHAPPELL, OF NEW YORK, N. Y., ASSIGNOR TO LOUISA LAWRENCE, OF SAME PLACE.

LETTER-FILE.

SPECIFICATION forming part of Letters Patent No. 379,049, dated March 6, 1888.

Application filed September 1, 1887. Serial No. 248,497. (No model.)

To all whom it may concern.

Be it known that I, GEORGE F. CHAPPELL, a citizen of the United States, and a resident of New York city, in the county of New York and State of New York, have invented certain new and useful Improvements in Letter-Files, of which the following is a specification.

My invention relates to that class of letter-files in which impaling and transfer wires are employed, and in which one or the other of said wires is movable.

Heretofore the movable wires have been hinged to vibrate, also to turn about their vertical axes, and also to slide both longitudinally and obliquely upon the board or tablet on which the files have been arranged.

My invention has for its main object to provide a simple, cheap, durable, and efficient letter-file; and to these main ends and objects 20 consists in the features of construction and combinations of devices hereinafter more fully described, and particularly pointed out in the appended claims.

In the drawings which accompany this specification and form a part thereof, Figure 1 is a top view of a letter-file embodying my invention, the board upon which it is mounted being broken away to economize in space upon the sheet. Fig. 2 is a longitudinal vertical 30 section thereof, taken at the line xx of Fig. 1. Fig. 3 is a top view of a modification of my invention.

In the several views the same parts will be found designated by the same numerals of reference.

2 represents the base board or tablet, which may be of any desired shape, construction, or length. The puncturing or impaling wires are designated by the numeral 3 and the transfer-wires by the numeral 4.

Referring particularly to Figs. 1 and 2 of the drawings, 5 designates a base-plate, preferably of metal, to which the straight puncturing or impaling wires 3 are secured, said base-plate being fastened to the board 2 by means of screws 6, or otherwise. Said base-plate is formed or provided with a lateral extension, 7, to the extremity of which is pivoted, as at 8, an arm or lever, 9, upon which the hook-shaped transfer-wires 4 are secured. A spring or friction

catch, 10, fastened to the bed-plate by screws 11, is adapted to hold the lever 9 in its closed position and the transfer-wires in engagement with the impaling-wires. The lever 9 is preferably elongated, as at 12, to extend beyond the line of the wires when closed, and in practice I add enough to the length of the lever to extend it just over one of the side edges, 13, of the board. The object of thus lengthening the lever is to enable the same to be worked with greater facility and from a point remote from the wires, where the papers on file are not apt to be in the way or interfere.

In operation the letters or other papers to be filed are placed upon wires 3, while the lever 65 and the transfer-wires are swung rearwardly, as indicated by the dotted lines at Fig. 1. To close the file, either for the purpose of retaining the letters in place upon the wires 3 or to enable the removal of some letter below the top of the pile, the lever is vibrated forwardly into the position shown in full lines in Figs. 1 and 2, and the two sets of wires thus brought together or into alignment. If it be desired to displace any letter beneath the top, the letters above it are transferred to the wires 4, the lever with such transferred letters swung backwardly, and the desired letter then raised above the points of the impaling-wires, after which the file may be reclosed and the transferred letters shifted over on the impaling-wires again.

Referring now particularly to Fig. 3, it will be observed that instead of employing the plate 5, a narrow cross-bar, 5^a, is made use of, in 85 which the impaling-wires 3 are secured. The lever 9, it will be observed, is bent, and is shorter in this instance, and is pivoted at 8 nearer the center of the board and upon the latter. So, also, it will be noticed that the catch 10 is secured upon the board in lieu of upon a base-plate, as 5. The operation of the file shown at Fig. 3 is substantially the same as that of the file shown at the other figures. So far as the main feature of my invention is concerned, the cross-bar 5^a may be dispensed with and the impaling-wires secured to the board direct. It will be understood, moreover, that in lieu of having the transfer-wires mounted upon the lever and movable, the punctur- 90 95 100

ing-wires may be secured thereupon and the transfer-wires arranged fixedly or immovably, the gist of my invention resting in having the movable wires (whether puncturing or transferring) secured upon a lever that is pivoted at one end exteriorly of the wires and adapted to vibrate in a plane parallel with that occupied by the board or tablet.

This improvement may be used in a file having only one transfer-wire and one puncturing-wire, as well as in the duplex file.

If deemed expedient or desirable, a stop or catch similar to that marked 10, or of other construction, may be employed to keep the lever in an open position when it is desired to have the wires apart, as illustrated by the dotted lines at Figs. 1 and 3.

What I claim as new, and desire to secure by Letters Patent, is—

20 1. In a letter-file, a lever (having one or more wires affixed thereto) pivoted vertically at or near one end and adapted to vibrate in a plane parallel with the board or tablet.

2. In a letter-file, a lever (having one or more wires affixed thereto) pivoted vertically at or near one end to vibrate, as set forth, and provided at its other end with a handle or extension.

3. In a letter-file, the combination of a lever (having one or more wires affixed thereto) pivoted vertically at or near one end to vibrate, as set forth, and a catch or retaining device to keep said lever in its closed position.

4. In a letter-file, the combination of the base-plate 5, the duplex puncturing-wires, the lever 9, pivoted vertically at or near one end beyond said wires to vibrate, as set forth, and having affixed thereto the duplex transfer-wires.

Signed at New York, in the county of New York and State of New York, this 15th day of August, A. D. 1887.

GEORGE F. CHAPPELL.
